UNITED STATES PATENT OFFICE.

ALPHEUS FAY, OF LOUISVILLE, KENTUCKY.

CREAM-SEPARATOR AND CHURN.

1,072,219.

Specification of Letters Patent.

Patented Sept. 2, 1913.

Application filed December 26, 1911, Serial No. 667,782. Renewed February 27, 1913. Serial No. 751,185.

To all whom it may concern:

Be it known that I, ALPHEUS FAY, a citizen of the United States, and a resident of Louisville, in the county of Jefferson and State of Kentucky, have invented a certain new and useful Cream-Separator and Churn, of which the following is a specification.

The object of my invention is to provide improved means for the performance of such processes in connection with the treatment of cream, milk or butter as require either mechanical agitation or aeration, or both.

The processes to which my invention is most applicable will hereinafter be more fully described and claimed.

My object also is to simplify the construction of apparatus of this character, and to add to its efficiency and durability.

My invention consists in the details of construction and arrangement, as will hereinafter be more fully described and claimed.

In the drawing: Figure 1 is a vertical sectional side elevation of a device embodying my invention. Fig. 2 is a plan view of part of my device, illustrating the manner in which it operates. Fig. 3 is a detail view of means for securing the operating parts to the vessel, being a modification from the means illustrated in Fig. 1.

In my present invention, the device is characterized by the co-action of two agitators, so that each acts as the brake to the other. Each agitator 1 is of such design as to produce a centrifugal impelling effect on the liquid, and each is mounted on a shaft 2, these shafts being journaled in a bracket 3 extending across the top of the vessel 4, and suitably supported, as will be later described. The transverse shaft 5 carries the correlated members 5^a and 5^b, which have laterally extended hubs 5^{a'} and 5^{b'} with which they turn loosely on the shaft 5.

These members 5^a and 5^b have hollow sides presented toward each other, in which they inclose the correlative gearing 5^c, comprising a driving gear 5^{c'} rigid on the shaft 5, a differential gear 5^{c''} loosely turning on a stud in the member 5^a and planetary to the gear 5^{c'}, and a gear 5^{c'''} rigid on the member 5^b, with which said gear 5^{c''} is also

planetary. This varies the speeds according to the resistance on the respective members. The hubs of the members extend to 55 the bearings on the bracket 3 at the sides, and the members also bear against the driving gear 5^{c'}, inside, so that end play of the members on the shaft 5 is prevented, and they are maintained in slightly separated 60 relation. Each member 5^a or 5^b has a bevel gear 5^d or 5^e, respectively, mounted on its hub, being held thereon to rotate therewith by set screws. The agitator shafts 2 have bevel pinions 2^a rigid thereon, and these 65 mesh with the bevel gears 5^d and 5^e.

The bearings 5' of the shaft 5 are detachably mounted on the bracket 3, and are located outside the agitator shafts, at the sides, as are also the bevel gears 5^d and 5^e, 70 which thus mesh with the pinions 2^a on the outer sides of said pinions. By having the bearings 5' detachable from the bracket 3, the assemblage of the machine is facilitated, and, especially, is of advantage in allowing 75 the driving gear 5^{c'}, of the correlated mechanism, to be rigidly secured to the shaft 5 before assemblage. Thus, this gear may be pressed onto the shaft, so that it is practically impossible for it to become loosened. 80 I have found from experience that, since the gear 5' must drive both agitators, the strain thereon is excessive, and any means that may be employed to secure it to the shaft after the shaft is in place, such as a 85 pin, is inadequate, with the result that the gear may become loosened from the shaft, rendering the entire mechanism inoperative and requiring complete disassemblage of the device in order to repair it. 90

I prefer to attach the bearings 5' to the bracket 3 by providing the bracket with upwardly extended bosses 5'', which are hollow, so that sockets are formed, receiving shanks 5''' of said bearings 5'. The lower 95 ends of the bosses 5'' have clamping screws 5'''' passing up into the lower ends of the shanks 5''', to bind the bearings in position. The shanks 5''' are terminated short of the bottoms of the sockets, so that the 100 shoulders on the bearings, where the shanks join the bearings, are drawn firmly against the tops of the bosses. Thus, the bearings may be practically as firmly attached to the

bracket as if they were formed integrally therewith, yet allow of the advantageous construction above described. Bearings 2' are provided for the upper ends of the agitator shafts 2, integrally formed on the bracket 3, and located thereon inwardly from said shafts to take over the pinions 2^a. These, with the other bearings 2'', in the bracket 3 below the pinions 2^a, serve to support the shafts in the mechanism, end play being prevented by the pinions.

Each agitator 1 comprises the tubular shaft 1^a and upper member 1', integrally formed, as here illustrated, and a lower member 1'' attached to the member 1'. The tubular shaft 1^a has, also integral with it, a hub 1^{a'} which is secured to the shaft 2 by a set screw, so that the tubular shaft 1^a and its agitator members may be adjusted up or down on the shaft 2. This hub 1^{a'} joins its tubular shaft by arms 1^{a''}, so that the upper end of said tubular shaft is left open for the admission of air. The bracket 3 is curved up, or arched over the vessel, so that the hubs 1^a may be adjusted above the rim of the vessel, whereby the liquid in the vessel may reach a level close to the rim, without overflowing the upper ends of the tubular shafts, where such a height of the liquid may be desirable.

The driving shaft 5 is turned by a handle 6, and, owing to the location of the bearings of this shaft outside the agitator shafts, not only is a more stable support for the shaft provided, but the handle may have a better formation, as may be understood on inspection of the drawing.

Each member 1' or 1'' of an agitator 1 consists in a plane body part 1^b or 1^{b''}, respectively, with triangular parts 1^c or 1^{c''}, respectively, bent at right angles thereto, at intervals therearound, with intervening straight parts 1^d or 1^{d''}, of the periphery of the plane body part left intact and exposed, as is best shown in Fig. 1. These lower and upper members, thus formed, are assembled inversely, with the triangular parts of one embracing those of the other. Preferably, the upper one has said parts embracing the corresponding parts of the lower one, so that there will be no lodgment of solid particles, as of butter, between the parts. The members are secured together by passing bent-over points 1^e of the triangles 1^c on the upper member 1' through slots 1^f in the triangles 1^{c''} of the lower member 1'', and passing similar points 1^{e''} on the lower member 1'' through similar slots 1^f in the upper member. The result of such assemblage of these parts is a box-like agitator of polygonal form, some of the sides of which are closed and the others open. On account of the triangular shape of the parts 1^c and 1^{c''}, the closed sides will lack triangular regions which merge with

the open sides and thus add to the area of the openings from the interior of the agitator, which these open sides constitute.

By providing a series of the slots 1^f and 1^f, respectively, in the triangular parts of the upper and lower members, in vertical alinement, the distance between the plane body parts of the members may be varied, it only being necessary to insert the points of the triangles into correspondingly different slots. The upper member has a free, unobstructed opening around the shaft 2, to allow ready circulation of air, from the open upper end of the tubular shaft 1^a down into the interior of the agitator, but the lower member fits snugly around the shaft, and thereby serves to support the agitator at its lower end, to maintain it concentric and in alinement with its shaft.

The closed sides of the box-like agitators being straight, and therefore presenting their surfaces against the liquid as the agitators rotate, an impelling action is exerted, forcing the liquid away from the exteriors of the agitators and producing a partial vacuum in each hollow interior, so that the flow of air, before mentioned, is inducted down into said hollow interiors of the agitators. Thus, the air drawn into said interiors, mixing with the liquid drawn therefrom, will be carried out into the main body of liquid in the vessel. A circulation of liquid and air will thus be set up in the liquid, amounting to a combined aerating and mechanical agitation.

The coöperation of the agitators 1 is such that there is a collision of the liquid particles at the middle of the vessel, and an outward ebullition at one side thereof, with a corresponding inward ebullition at the other side, with a continuous circulation of the mingled liquid and air upward and downward, and around the interior of the vessel. The consequence is that the entire contents of the vessel are brought into a state of ebullition, or bubbling, resembling very much in appearance the boiling of liquid under the action of heat; of course, however, no such temperature is ever used in the processes for which this apparatus is adapted, as a boiling temperature is well known to be injurious to all milk products. It is by this utilization of the effects of boiling, or ebullition, in a mechanical way, without entailing the injurious effects of heat, that some of the more important results of the processes to be described are reached. By adjusting the lower member from the upper one, the effect of the agitator may be varied to suit the use to which the apparatus is applied.

It will be observed that the impelling is effected by means of peripherally located means only, leaving the interior of the agitator smooth and unobstructed; also that the openings constituted by the open sides

of the polygonal agitator are themselves polygonal, having, specifically, horizontal upper and lower sides and angular lateral sides, so that the width of a respective opening is greater at its middle, midway between the upper and lower plane body portions 1^a and 1^b , respectively, than at its top or bottom, adjacent the body portions. The effect of an opening of such a shape is to cause a congestion of the outward flow of liquid and air from the interior of the agitator, in the plane surrounding the middle region between the upper and lower plane body parts, due to the greater outflow from the widened parts of the openings. This results in a more intimate intermingling of the liquid and air particles, adding to the completeness of the aeration while allowing an undiminished mechanical agitation by the upper and lower wider regions of the triangular parts 1^c and 1^d , forming the closed sides.

The tangential, and radially inward and outward ebullition above described, may be more readily understood upon inspection of Fig. 2. The small black arrows indicate the flow of the liquid and air, and the large arrows indicate the direction of rotation of the agitators to produce such flow.

It will be understood that the agitating effect are attainable, and the ebullition may be produced, regardless of the presence of the correlative gearing for operatively mounting the gears 5^a and 5^b on the shaft 5, since the direction of rotation of the agitators would be unaltered if the gears 5^a and 5^b were fixed directly on the shaft 5. The correlative gearing is preferable, as shown, because it is found in practice to allow a much more efficient application of power to the two agitators provided to operate in the peculiar way herein described. Furthermore, it will be understood that each of the agitators 1 acts as a brake for the other, for the liquid emerging from one to collide with the other agitator, as well as with the liquid emerging from said other agitator. Since the correlative gearing herein allows the speeds of the agitators to vary with respect to each other, its use will allow a variation in the relative arrangement of the agitators, so that they will at times present their open sides toward each other, and at other times present an open side to a closed side. When open sides come opposite, collision of liquid particles will be the only breaking means, and this relation of the agitators will also involve the opposition of closed sides, which will co-operate to impel the liquid from between the agitators. This is the relation illustrated in Fig. 2. When open and closed sides are opposed, the closed side will act as a mechanical brake to the liquid emerging from the open side. These different conditions attending the variation in relation

of the agitators permitted by the correlative gearing are described in view of the evident value of constant variation in the action on the liquid, tending to a more thorough and rapid operation on each particle of the liquid, but always with the same general character, that of ebullition, before alluded to.

For separating and churning, fresh sweet milk is placed in the vessel, to the amount of about half its capacity, the upper ends of the tubular shafts 1^a being above the upper surface of the liquid, as before described. The milk is then agitated by the operation of the mechanism, to cause the ebullition before referred to, and thoroughly aerate the milk. The milk is preferably introduced at a temperature of from 40 to 50 degrees Fahrenheit, with the atmospheric temperature at about 70 degrees. After the combined agitation and aeration have been continued for from three to ten minutes, the liquid is allowed to rest for a few minutes, when the cream will have completely separated from the other milk elements, and will have risen to the top of the body of liquid. For this separating process, the vessel may be filled to nearly its capacity, if desired, instead of only half thereof, as above described, which will necessitate adjustment of the agitators 1 to their uppermost positions. The better results are attained, however, with the agitators near the bottom of the vessel, as indicated, although the quantity of liquid operated upon will be smaller.

After the separation above described has become complete, the skimmed milk is drawn off, leaving the separated cream in the vessel. By varying the volume of skimmed milk drawn off, the cream may be left with any desired proportion of butter fat. When the desired proportion of skimmed milk has been drawn off, the agitation is resumed to churn the cream. For this operation, the lowered agitators are especially desirable. The temperature of the cream will by this time have risen to approximately that of the atmosphere, or from 60 to 75 degrees Fahrenheit, and the churning agitation and aeration are continued at this temperature until the butter is separated from the cream, ordinarily requiring from three to five minutes. The butter may then be removed and worked in the usual manner, and, for conveniently removing the butter, the bracket 3 may be removed from the vessel along with the shafts and the agitators, leaving free access to the vessel, and leaving the entire interior of the vessel smooth, facilitating a thorough removal of the butter and permitting a thorough cleansing of the interior after the residue from the churning has been withdrawn.

If it be desired, the residue from the churning may be left in the vessel, and the skimmed milk that had been withdrawn

after the separating operation may be then added to the residue thus remaining, and the agitators 1 again introduced and operated to thoroughly mix them, resulting in 5 the production of a good serviceable fresh sweet milk, which contains all the natural solids of the milk except the butter fats, and which has the natural flavors of fresh sweet milk.

10 If it be desired to produce a high grade of buttermilk, the skimmed milk may be placed in the vessel with the churning residue, and before introducing the agitators, the liquids allowed to become sour, reaching 15 the condition of clabber. Then when the agitators are introduced and the agitation and aeration of the soured liquids effected, a good quality of finely aerated buttermilk will result. The souring of the liquids may 20 be facilitated by the use of a suitable ferment. This souring may also be effected with the skimmed milk alone, allowing it to reach the condition of clabber, and then agitating it and aerating it; such treatment 25 of skimmed milk is advantageous when the cream therefrom has been used as cream, and not for the production of butter, leaving no residue for mixture with the skimmed milk.

30 In the treatment of either of the above clabbers, the adjustment of the agitator members is of advantage, since the increased distance between them, and the increased size of the openings in proportion to the increase in area of the closed sides, greatly facilitates the driving them in operating upon the clabber, which naturally is of heavy and somewhat viscous consistency.

A poor quality of butter may be operated 40 upon, to improve it, by the use of my invention, placing the inferior butter in a suitable amount of pure water in the vessel and agitating it and aerating it in the manner above described, but at a temperature of 50 45 or 60 degrees Fahrenheit. The butter may be granulated to permit a most efficient purifying action of the air thereon, and of the water, which may be withdrawn and fresh water supplied, as required; the entire operation 50 results in producing the butter granules in a neutral state with their impurities eliminated. The neutral granules may then be removed and salted and worked and otherwise treated according to good practice 55 in the production and marketing of palatable fresh butter, with which it is identical. Furthermore, if desired, the butter granules above alluded to may be mixed with sweet milk to produce a high quality of cream of 60 any desired percentage of butter fat, of smooth consistency, thoroughly fresh, sweet and pure, and adaptable for all the purposes that a good cream is used for.

This combined agitation and aeration is 65 especially applicable to the process of whip-

ping cream. Usually, a cream to be whipped must be very rich in butter fats, in order to attain the peculiar fluffy consistency so much desired. In combining the mechanical agitation of the cream with the peculiarly effective aeration and ebullition which my apparatus affords, a cream with only a moderate fatty consistency may be employed, because the aeration is of such thoroughness, with respect to the mechanical agitation that the cream receives, that the desired consistency of the whipped cream is readily and amply attained with an operation of only from three to five minutes. For whipping cream, the agitators should be close together 70 and rotated at a high speed.

75 My apparatus is also well adapted for producing homogenized products, such as preparations to be used as butter, as oleomargarin, or as butterin. For this purpose, 80 the apparatus is placed over a source of heat, a stove or burner of suitable character, so that the temperature of the contents of the vessel may be raised gradually and moderately while the agitating and aerating operation is conducted in the vessel. Thus, 85 for preparing homogenized butter and milk, equal parts of the substances are taken, the milk having a temperature of 50 degrees Fahrenheit, approximately, and the butter 90 and milk placed together in the vessel, over the source of heat, and the heat regulated so as to raise the temperature of the mixed contents of the vessel to 90 degrees Fahrenheit in about three minutes, during which 95 time the agitation and aeration, with the ebullition thus resulting, is maintained in the contents of the vessel. At the end of this operation, the milk and butter will be found to have merged into a single homogeneous 100 mass, having many of the characteristics of good butter and well adapted for use as such by the user of the apparatus. When properly labeled, this homogenized article also becomes a salable product, and introduces 105 an opportunity for marked economy in either case, since the cost of the resultant product is only the mean between the cost of the butter and that of the milk.

110 When homogenized oleomargarin is to be made, the oleomargarin is taken instead of the butter, and when butterin is to be produced in homogenized form, lard is used to merge with the milk; equal quantities of the fatty ingredients are taken in either case, 115 and the temperature of the milk is initially about 50 degrees Fahrenheit, as with the butter, gradually increasing the temperature of the mixture to 90 degrees Fahrenheit during the agitation and ebullition. Such homogenized products are superior in food value 120 to the pure fatty ingredients employed, inasmuch as they contain the solids of the milk other than the fats. The convenience 125 with which those products are produced by 130

my apparatus makes them available to the private consumer, for domestic preparation, with the advantages of economy and improved food value mentioned.

5 The vessel that contains the substances operated upon may be of metal, as illustrated in Figs. 1 and 2, this being especially suitable for treatment with heat, as described above. With such a vessel, attachment of the bracket 3 directly to the vessel is avoided by providing a base 13, on which the vessel 4 rests, provided with standards 13^a having heads 13^b with sockets to receive shanks 3^a of the bracket 3. Clamping 10 screws 13^c take into the lower ends of the shanks, to draw the bracket snugly against the tops of the standards. If the vessel be of wood, brackets 13^d, similar to the heads 13^b of the standards, are screwed to the outer 15 sides of the wooden vessel 4', near its rim, as shown in Fig. 3. Into these brackets the shanks 3^a of the bracket 3 are clamped by the screws 13^c, so that the bracket is secured directly to the vessel, as is permissible with 20 a wooden vessel. Metal vessels are generally enameled, making it impractical to have the attachment of the bracket directly on the vessel, owing to the liability to injury of the finish. For conveniently drawing off 25 liquids, the vessel is preferably provided with a faucet 4^a, as shown in Fig. 2.

The several processes have been explained in detail herein as appropriate examples of the uses of my apparatus. Other 30 advantageous uses will be suggested in the use of my invention, and divers minor modifications may occur in its adaptation to such uses; therefore I do not wish to be understood as limiting myself to the precise 35 details herein described and illustrated, but

What I claim as new and desire to secure by Letters Patent is:

1. In a device of the character described, 40 juxtaposed hollow agitators, each with a straight side presented at an angle to the line of rotation, and an opening from the interior of the agitator, and an air inlet to said agitator, means for adjusting the

area of said straight side and of said opening, and means for rotating the agitators in opposed directions.

2. In a device of the character described, juxtaposed polygonal hollow agitators, each with some of its sides closed and others open, and with plane top and bottom members 45 conforming to the planes of rotation in their respective positions, and each having an atmospheric inlet to its hollow interior, and means for rotating the agitators in opposed directions.

3. In a device of the character described, the combination of a bracket, vertical bearings therein, bosses thereon flanking the vertical bearings, each boss being hollow in its upper region to form a socket, and horizontal 60 bearings, each having a shank leaving a shoulder where the shank joins the bearing, the tops of said bosses being adapted to receive the shoulders of the bearings and the sockets of the bosses being adapted to receive 65 the shanks, said bosses having openings in their bottoms and said shanks having openings in their bottoms, and clamping screws taking through the openings in the bottoms of the bosses and threaded into the openings 70 in the bottoms of the shanks, to draw said shoulders against the tops of the bosses and detachably secure said horizontal bearings 75 to the bracket.

4. In a device of the character described, 80 the combination of a container for liquid to be treated, juxtaposed aerating agitators mounted therein for rotation on upright axes, each of said agitators comprising a plane top plate, a plane bottom plate spaced 85 from the top plate, the inclosed space having communication laterally with the space surrounding the agitators, an air inlet to the space between the top and bottom plates, and means permitting adjustment of one of 90 said plates toward and from the other, and means for rotating the agitators.

ALPHEUS FAY.
